UNITED STATES PATENT OFFICE.

WILLARD N. PACKER, OF SHELBY, OHIO, ASSIGNOR TO THE SHELBY SPECIALTY COMPANY, OF SHELBY, OHIO, A CORPORATION OF ARIZONA TERRITORY.

VENTILATING SASH-LOCK.

SPECIFICATION forming part of Letters Patent No. 769,012, dated August 30, 1904.

Application filed April 11, 1903. Renewed May 6, 1904. Serial No. 206,642. (No model.)

To all whom it may concern:

Be it known that I, WILLARD N. PACKER, a citizen of the United States, residing at Shelby, in the county of Richland and State of Ohio, have invented certain new and useful Improvements in Ventilating Sash-Locks, of which the following is a specification.

This invention relates to window-buttons of the type providing means for locking or fastening together the meeting-rails of window-sashes; and it has for its object to provide an improved sash-lock of this character which may be properly termed a "ventilating" sash-lock, as the same comprises means for securely locking the sashes together either in a closed position or when partially opened for the purposes of ventilation by permitting the window to be partly open at top or bottom or both at top and bottom and still be secure against opening from unauthorized agencies outside of the window.

To this end the invention contemplates a simple and practical type of sash-lock embodying a minimum number of working elements, while at the same time providing a secure lock under any conditions indicated and at the same time not interfering with the complete opening of either or both sashes whenever this is desired.

Another object of the invention is to provide a sash-lock construction the several parts of which may be made from stampings in a simple and practical manner.

With these and many other objects in view, which will more readily appear as the nature of the invention is better understood, the same consists in the novel construction, combination, and arrangement of parts, which will hereinafter be more fully described, illustrated, and claimed.

The essential features of the invention involved in the novel manner of separably interlocking the separate members of the lock to permit of the various adjustments of the sashes are necessarily susceptible to modification from a structural standpoint without departing from the scope of the invention;

but a preferable embodiment thereof is shown in the accompanying drawings, in which—

Figure 1 is a perspective view of a sash-lock 50 constructed in accordance with this invention and shown in position for holding the meeting-rails locked together when both sashes are closed. Fig. 2 is a vertical sectional view of the lock with the parts in the relation 55 shown in Fig. 1. Fig. 3 is a similar view with the parts shown in the relation which they occupy when either or both sashes are partly open for ventilating purposes. Fig. 4 is a similar view showing the separable interlocking members separated to permit of the complete opening of either sash. Fig. 5 is a rear perspective view showing the arrangement of parts illustrated in Fig. 3. Fig. 6 is a perspective view of the complete sash- 65 lock device, showing the members and constituent elements separated.

Like reference characters designate corresponding parts throughout the several figures of the drawings.

The complete sash-lock device constructed in any suitable manner and of any suitable material as an entirety consists of two separate members A and B, carried, respectively, by the separate meeting-rails of the upper 75 and lower sashes. While the separate members could be respectively arranged on either of the meeting-rails, still the preferable and practical arrangement, as shown in the drawings, consists in applying the member A to 80 the meeting-rail of the lower sash L and the member B to the meeting-rail of the upper sash U of the window. So for convenience in understanding the action of the lock the arrangement illustrated will be specifically referred to. The sash-lock member A, which is fastened to the upper face of the meeting-rail of the lower sash L, essentially comprises a base-plate 1 and a vertically-rocking fastening-lever element 2, mounted thereon. The 85 base-plate 1 is of a flattened form to rest flat upon the rail to which it is attached and is preferably provided at the under side thereof with a retaining lug or projection 3, fitting in

a correspondingly shaped and sized mortise 4 in the meeting-rail to provide for firmly interlocking the member A with the said meeting-rail and holding the same against creeping or displacement incident to any heavy strain or pressure imposed thereon. In addition to the retaining lug or projection 3 the said base-plate 1 is further provided with the perforated fastener-ears 5, receiving the screws or other fasteners to secure the plate to the rail, and at its inner edge the plate 5 overhangs the adjacent edge of the rail to produce an overhanging guard-lip 6, which spans the joint between the meeting-rails when closed and effectually prevents the introduction of a knife or other instrument from the outside between the meeting sash-rails. In conjunction with the overhanging guard-lip 6 the said base-plate 1 is also provided, at the inner corners thereof, with the upstanding auxiliary guard-ears 7 of a shouldered formation to also bridge the joint between the meeting-rails and prevent the introduction of an instrument laterally beneath the latch or coupling element 8 of the member B, to be presently referred to.

The rocking fastening-lever element 2 is mounted at a point intermediate its ends upon a horizontal pivot 9, passing therethrough and also through a pair of upstanding bearing-ears 10, arising from the base-plate 1 and between which the lever 2 is supported. This lever is of peculiar formation to provide for fastening or locking the two sashes either in closed or partially open positions. At one side of its horizontal pivotal support 9 the lever is formed with a substantially straight coupling-arm 11, provided at its terminal with a "T-head" 12, producing oppositely-projecting holding-lugs. This T-head 12 and the holding-lugs, constituting a part thereof, are preferably formed by slitting the inner end of the arm 11 a short distance, as at 13, and bending the portions at opposite sides of the slit, respectively, to opposite sides of the arm, thereby forming the lugs or head which serve to hold the two members of the sash-lock separably interlocked in the manner illustrated in the drawings. At the other side of its pivot the fastening-lever element 2 is formed with a vertically arched or curved catch-arm 14 substantially in the form of a hook and provided at its terminal with a shouldered locking-tip 15, having a play with in the clearance-notch 16 at the outer end of the base-plate 1 and adapted to have a snapping engagement with the swinging end of the latch or coupling element 8 of the lock member B. In connection with the construction of the fastening-lever element 2 it is also to be observed that the separate arm members 11 and 14 of the lever are angularly related and disposed in planes substantially oblique to each other to permit of the same

assuming the positions plainly shown, respectively, in Figs. 2 and 3 of the drawings.

Referring more particularly to the construction of the lock member B, it is to be observed that the latch or coupling element 8 is in the form of a vertically-swinging slotted link of an oblong form and usually constructed with a reinforcing-rib 17 about the edge thereof. In addition to the rib 17 the latch element 8 is provided with a web portion 18, having a T-shaped slot consisting of a longitudinal section 19, extending substantially the full length of the latch, and a cross-slot 20 in communication with the slot-section 19 and at the extreme inner end thereof, said cross-slot 20 forming oppositely-located clearance-notches for the oppositely-projecting holding-lugs 12 of the coupling-arm 11, as will hereinafter appear. At the inner end thereof the latch element 8 is formed with a cylindrical pivot-bar member 21, having a flattened side portion 22 and terminal pivots 23 turning in the oppositely-located pivot-ears 24, stamped up from an attaching or base plate 25, which is secured to the upper face of the meeting-rail of the upper sash U. The attaching-plate 25 is also formed with perforated fastener-ears 26 for the screws or other fasteners and at an intermediate point with the integral curved pressure-tongue 27, bent forwardly over the pivot-bar member 21 and adapted to have a spring or friction pressure thereon and also to have a holding engagement with the flattened side portion 22 of the said pivot-bar 21 when the latch is in its horizontal position over the fastening-lever element 2, as plainly shown in Fig. 2 of the drawings.

With the meeting-rails in their matching closed positions both sashes are locked against opening by moving the slotted latch or link 8 downward over the fastening-lever 2, so that the outer end edge of the longitudinal slot 19 may be forced into snapping engagement with the shouldered locking-tip 15 of the fastening-lever 2. In this position of parts the lever 2 projects upwardly through the slot 19, and the pressure-tongue 27 assists in holding the latch in its locked position by engagement with the flattened side portion 22. If it is desired to arrange the parts so as to provide for a separation of the meeting-rails with a partial opening of either or both of the sashes at their other ends, the free end of the latch 8 is drawn up, thereby rocking the fastening-lever on its pivot to a position which permits of the ready disengagement of the latch from the tip 15 of the lever. Then it is only necessary to move the upper sash downward or the lower sash upward to slidably carry the coupled parts to the position shown in Figs. 3 and 5 of the drawings. In this movement, since the T-head 12 of the coupling-arm 11 moves through the longitudinal slot-section 19 toward the unpivoted end of

the latch, it is impossible for the elements to become separated, and they consequently remain slidably interlocked or coupled in any and all positions. When the meeting-rails 5 are brought together again, the parts are locked by being moved to the positions shown in Fig. 2, as already explained, and in the horizontal locked position of the latch 8 the same lies flat upon the plate 1 between the opposite site auxiliary guard-ears 7 thereof.

Should it be desired to uncouple or separate the members A and B to permit of the complete opening of either of the sashes at the time of raising the free end of the latch 15 to disengage it from the catch-arm 14 of the lever, the inner coupling-arm 11 of such lever is held down by the finger to permit the T-head 12 to remain in the plane of the clearance slot-section 20 until the latch 8 has been 20 raised entirely over the said T-head to the position shown in Fig. 4 and in which position the two members are entirely uncoupled for the purpose indicated.

From the foregoing it is thought that the 25 construction, operation, and many advantages of the herein-described ventilating sash-lock will be readily apparent without further description, and it will also be understood that changes in the form, proportion, and minor 30 details of construction may be resorted to without departing from the spirit of the invention or sacrificing any of the advantages thereof.

Having thus described the invention, what 35 is claimed, and desired to be secured by Letters Patent, is—

1. In a sash-lock, a fastening-lever carried by one sash and provided with holding-lugs, and a pivotally-mounted swinging latch carried 40 by the other sash and having a longitudinally-slotted portion slidably interlocking with the lugged part of the lever.

2. In a sash-lock, a lever element carried by one sash, and a swinging latch element carried 45 by the other sash and having a longitudinally-slotted portion interlocking with and receiving wholly therein said lever element.

3. In a sash-lock, a lever element carried by one sash, and a swinging latch element carried 50 by the other sash and having a longitudinally-slotted portion slidably interlocking with the lever element and also having a snapping engagement therewith.

4. In a sash-lock, a vertically-rocking lever 55 element carried by one sash, and a vertically-

swinging latch element carried by the other sash and having a separable and slideable interlocked connection with the lever element.

5. In a sash-lock, a vertically-rocking lever element carried by one sash, and a vertically- 60 swinging latch element carried by the other sash and having a separable and slideable interlocking connection with the lever element, said connection comprising means for maintaining the coupled relation of the elements 65 during and after separation of the meeting-rails, and also comprising means for permitting of the disconnection of said elements prior to the opening of either sash.

6. In a sash-lock, a vertically-rocking fas- 70 tening-lever carried by one sash and provided with a coupling-arm having holding-lugs, and a vertically -swinging latch carried by the other sash and having a longitudinally-slotted portion slidably interlocking with the lugged 75 coupling-arm of the lever.

7. In a sash-lock, a vertically-rocking fas- 80 tening-lever carried by one sash and having angularly-related catch and coupling arms respectively provided with a shouldered tip and lugs, and a slotted vertically-swinging latch carried by the other sash and slidably interlocked with the lug-carrying arm of the lever, said slotted latch also having a locking en- 85 gagement with the catch-arm of the lever. 85

8. In a sash-lock, a member carried by one sash consisting of a base-plate having a guard-lip and guard-ears at the joint, and a vertically - rocking fastening - lever pivotally mounted on the base-plate and provided with 90 angularly-related catch and coupling arms respectively, the latter having terminal holding-lugs, and a separate member carried by the other sash consisting of a base-plate having a spring pressure-tongue, and a vertically- 95 swinging latch having a pivot-bar journaled upon the base-plate and provided with a flattened side engaged by said pressure-tongue, said latch being further provided within its body portion with a longitudinal coupling-slot for engagement with the coupling-arm of the lever and with a cross-slot at one extremity of the longitudinal slot to provide 100 clearance for the lugs of said coupling-arm.

In testimony whereof I affix my signature in 105 presence of two witnesses.
